ELECTRIC REGULATION.

1,351,055.

Specification of Letters Patent. Patented Aug. 31, 1920.

Application filed February 17, 1917. Serial No. 149,222.

To all whom it may concern:

Be it known that we, GEORGE G. MILNE and JOHN L. CREVELING, residing at Rye, county of Westchester, and State of New York, and White Plains, county of Westchester, and State of New York, respectively, have invented the new and useful Improvement in Electric Regulation set forth in the annexed specification, wherein our invention is explained, with reference to the accompanying drawings.

Our invention pertains to that class of electric regulation wherein it is desired to automatically control the operation of a dynamo electric machine.

One of the principal objects of our invention is to provide a simple and rugged type of regulating means which may be so incorporated into the structure of a dynamo electric machine that the same may be considered as a self-contained, self-regulating, dynamo.

A further object of our invention is to cause such a dynamo to be self-regulating in response to fluctuations in a plurality of qualities or quantities so as to regulate the dynamo in a desired manner in response thereto.

A further object of our invention is to provide means whereby such a dynamo may be caused to respond automatically to such a plurality of fluctuations in a more or less independent manner as may be desired.

In the drawing, Figure I is a partial section and partial elevation of one form of dynamo in which our invention is embodied:

Fig. II is a partial section of the dynamo shown in Fig. I, taken on the line A—B, showing a portion thereof in a different position of operation than shown in Fig. I;

Fig. III is a diagrammatic representation of a system employing one of the preferred embodiments of our invention;

Fig. IV is a section of a portion of our invention; and

Fig. V is a modification which may be made in the system of Fig. III.

In Fig. I, 1 represents the housing or frame of a dynamo provided with the armature 2, having commutator 3, and carried by the shaft indicated at 4, which is supported in any suitable type of bearings, not shown. The armature is revolved between polar faces 5 and 6, the pole piece 5 being a por-

tion of the frame 1, while the polar face 6 is bored into the member 7, fitted snugly into the frame 1 and secured in place as by bolts or screws 8. The member 7 is surrounded by the coils 9 which may be of any desired character to set up the proper field for the dynamo. The member 7 is also bored to form a pole piece, as indicated at 10, and the frame 1 is bored out to form a corresponding polar surface as indicated at 11. Within the polar surfaces or pole pieces indicated at 10 and 11, we mount a suitable bobbin or spool, preferably of brass or other non-magnetic material, indicated at 12, which may be held firmly in place by any suitable means, for example lugs 13 and screws 14. This bobbin is shown in section in Fig. II as wound with a fine wire 15 which we use when the same is to be employed in shunt to the dynamo, and is so shaped as to engage and hold in place the annular ball-bearings 16 which support the central shaft or cylinder 18, preferably of iron, and provided at its extremities with the cam-like extensions 19 and 20 which are shown in Fig. II as revolved 90° from the position shown in Fig. I. The members 19 and 20 may be firmly united with the member 18 in any suitable manner, as for example split and held thereon as by means of a screw, shown in dotted lines in Fig. I.

In Fig. I there is shown an adjustable spring 21 engaging a band 22 passing over sheave or roller 23 which tends to rotate members 19—20 in a clockwise direction, while movement in this direction is limited as by means of stop 24.

In Fig. IV the bobbin or spool 12 is shown as provided with a shunt winding 25 and a series winding 26, forming a compound winding which may be used when desired.

In Fig. III there is shown a generator of the type shown in Figs. I and II, possessing a plurality of magnetic shunts which may be of similar construction to the ones shown in Figs. I and II, each capable of regulating the generator and respectively responsive to different functions of the generator's operation. In this figure there is shown a system of electrical distribution wherein a generator is used to charge a storage battery and operate lamps or other translating devices in conjunction therewith, and our invention is particularly ap-

plicable to this type of system, more especially when the generator is driven at variable and intermittent speeds, under which condition it is often desirable to regulate the generator in response to voltage fluctuations and at other times in response to current fluctuations. In this figure the magnetic shunt comprising members 18, 19 and 20 is surrounded with the voltage coil 15, 5 as shown in Fig. II, which is in shunt across the generator mains; while the magnetic shunt possessing members 18^a, 19^a and 20^a is shown as surrounded by a series winding 27 which is in series with the generator 10 and which may, of course, be placed in series with the battery circuit, as shown in Fig. V, 15 if desired.

An operation of our invention is substantially as follows: With the dynamo of Fig. 20 I used as a generator, for example, if its armature be revolved at appreciable speed and if the coils 9 be properly wound, its field will build up in a well known manner and there will be present two magnetic 25 circuits, one from the pole piece 6 through armature 2, pole piece 5 and shell 1 to the member 7, and the other from pole piece 10, through member 20, member 18 and member 19 to the pole piece 11, and then through 30 shell 1 to the member 7. The flux through the first named magnetic circuit will tend to increase the voltage of the generator, while the flux through the second circuit by tending to shunt the lines of force away from 35 the useful generator field will tend to weaken or cut down the electromotive force of the generator, depending, of course, upon the number of lines thus shunted away from the main flux, which number of lines will 40 depend upon the position of the shunt members 19, 18 and 20, which in Fig. I are shown in such position as to shunt away very few lines from the main generating flux; while in Fig. II the said members are shown as 45 revolved 90° into a position where they shunt away a considerable of the magnetic lines from the main field. The spring 21 tends to hold the members 18, 19, 20 in the 50 position shown in Fig. I, while the tendency of the lines of force to leak from the pole piece 10 through said members to the pole piece 11 and the magnetization of the said members by the coil 15 when properly wound, tends to cause the said magnetic 55 shunting members to rotate in a counter-clockwise direction against the action of spring 21 into a position of greater shunting effect. And we so balance the tendency of the spring 21 or other equivalent means 60 tending to draw the said shunting members into the position shown in Fig. I, against the magnetic moment or torque tending to rotate the members into the position shown in Fig. II, that when the armature is revolving at the lowest speed capable of pro-

ducing the desired voltage across its brushes the said shunting members will shunt away from the main magnetic field a very small portion of the lines set up by the field coils. But, upon a very slight increase in voltage, 70 the shunting members are so revolved as to shunt away from the main field sufficient number of magnetic lines to so weaken the field that the voltage across the generator will be held substantially constant throughout the wide changes in speed. If desired, a series winding may be employed, as shown at 26 in Fig. IV, and the current output of the generator may be limited by the torque upon the magnetic shunt members, revolving the same against the action of the spring in a manner similar to that outlined above but responding to prevent a maximum current from being exceeded, instead of a maximum voltage. Or a compound winding, as 80 shown in Fig. IV, may be employed, and a composite regulation responsive to the resultant effect of current and voltage conditions may be effected.

In that modification shown in Fig. III, if 90 the voltage tend to increase above a predetermined limit, members 19 and 20 will tend to swing toward the position shown in the said figure, in such manner as to cut down the generating field and prevent a desired 95 adjustable voltage from being exceeded. While, on the other hand, if the current tend to exceed a predetermined limit, the shunting members 19^a and 20^a will tend to swing toward the position shown in the figure, 100 and, by cutting down the generating field, prevent this maximum desired current from being exceeded. Therefore, with the proper adjustment of the coils 15 and 27 and the respective torques opposing the magnetic 105 torque which may be a function of the current in said coils, the output of the generator may be regulated quite accurately, in such manner that it will be unable throughout wide increases in speed to maintain a voltage above the fully charged voltage of the battery. And, therefore, as the battery approaches charge, its current will taper off or cease, while an undesirably large current 110 will never be supplied to the battery nor will the generator be over-loaded, even though the battery voltage be very low, as for example when in a discharged state.

While in the system shown in Fig. III the total generator output is held from exceeding a predetermined limit, it will be plain that by placing winding 27 in series with the battery circuit, as coil 28 is shown in Fig. V, instead of the main circuit as shown in Fig. IV, the battery charging current 115 will be limited instead of the generator output.

It will be noted that we have produced a dynamo which may be regulated either in response to voltage fluctuations, current 120

fluctuations, jointly in response to current and voltage fluctuations, or independently in response to voltage or current fluctuations, as desired; and that our means for thus regulating the dynamo comprehend a rugged construction easily applied thereto and possessing no movable parts carrying current or having windings thereupon, and that such magnetic members automatically act to control the operation of the generator in response to a plurality of chosen operating functions.

We do not wish in any way to limit ourselves to any of the exact constructions or details of operation given above to illustrate an embodiment of our invention, for it will be obvious that wide departure may be made therein without departing from the spirit and scope thereof.

20 What we claim is:

1. In a dynamo having an armature and field exciting means, a plurality of means for regulating the dynamo by independently diverting the field away from said armature and responsive independently to voltage and current, respectively.

2. In a dynamo, the combination with an armature and means for maintaining a magnetic flux through said armature, of means for diverting a portion of the flux away from said armature comprehending a plurality of movable magnetic members and independently responsive means for controlling the positions thereof.

3. In a dynamo, the combination with an armature and means for maintaining a magnetic flux through said armature, of means for diverting a portion of the flux away from said armature comprehending a plurality of independently movable magnetic members and automatic means responsive to the dynamo's operation for controlling the positions thereof.

4. In a dynamo, the combination with an armature and means for maintaining a magnetic flux through said armature, of means for diverting a portion of the flux away from said armature comprehending a plurality of movable magnetic members and electromagnetic means responsive to voltage and to current of the dynamo for controlling the positions thereof whereby said members independently regulate the dynamo.

5. In a dynamo, the combination with an armature and means for maintaining a magnetic flux through said armature, of means for diverting a portion of the flux away from said armature comprehending a plurality of movable magnetic members and electromagnetic means responsive to a plurality of functions of the dynamo for independently controlling the positions thereof.

6. In a dynamo, the combination with an

armature and means for maintaining a magnetic flux through said armature, of means for diverting a portion of the flux away from said armature comprehending a plurality of movable magnetic members and electromagnetic means for automatically independently controlling the positions thereof, said electromagnetic means being responsive to current fluctuations and voltage fluctuations.

7. In a dynamo, the combination with an armature and means for maintaining a magnetic flux through said armature, of means for diverting a portion of the flux away from said armature comprehending a plurality of movable magnetic members and electromagnetic means for automatically independently controlling the positions thereof, one of said members being responsive to current fluctuations and another of said members being responsive to voltage fluctuations.

8. In a dynamo, the combination with an armature and means for maintaining a magnetic flux therethrough, of means for diverting a portion of said flux from said armature comprehending a plurality of independently movable magnetic members and electromagnetic means for independently controlling the positions thereof in response to a plurality of functions of operation of the dynamo.

9. The combination with a dynamo, storage battery, and translating devices, of means for regulating said dynamo comprehending a magnetic shunt the position of which is responsive to voltage fluctuations across the battery, and a magnetic shunt the position of which is responsive to current fluctuations.

10. The combination with a dynamo, storage battery and translating devices, of means for regulating said dynamo comprehending a magnetic shunt the position of which is responsive to voltage fluctuations across the battery, and a magnetic shunt the position of which is responsive to current fluctuations whereby the voltage impressed upon the battery and the current supplied by the generator are both held within predetermined limits.

11. The combination with a dynamo, storage battery and translating devices, of means for regulating said dynamo comprehending a magnetic shunt the position of which is responsive to voltage fluctuations across the battery, and a magnetic shunt the position of which is responsive to fluctuations in the current delivered to the battery.
